UNITED STATES PATENT OFFICE.

ARTHUR A. JAHE, OF FOREST PARK, ILLINOIS, ASSIGNOR OF ONE-HALF TO AUGUST E. SCHULTZ, OF CHICAGO, ILLINOIS.

WINDOW.

Application filed September 20, 1926. Serial No. 136,602.

My invention relates to windows and particularly to those windows employing swinging sashes. A sliding sash is also desirably employed in the preferred embodiment of the invention.

The invention has for its general object the provision of improved mechanism for imparting swinging movement to the sashes. When the invention is embodied in a window that also employs a sliding sash, a link so connects the two sashes that the movement imparted to one sash occasions movement of the other sash. Means are desirably employed for holding the sliding sash in various adjustments, such means operating through this sash to hold the second sash in adjustment. Such means desirably comprises an elongated member having notches or other holding formations spaced apart along the same and a second member in the form of a holding dog engageable with said holding formations, one of said formations being stationarily arranged upon the window frame and the other being provided upon the sliding sash. The angular relation of the swinging sash for any given position of the sliding sash is adjustable by changing the effective length of the aforesaid link. The effective length of the link is desirably adjustable by means of spaced apart notches therein which are adapted to receive a holding portion provided upon the sliding sash. Means are provided for holding the swinging link in close proximity to the sliding sash in all positions of this sash so that it may not accidentally fall at the end thereof which cooperates directly with the sliding sash to occasion bodily harm.

I will explain my invention more fully by reference to the accompanying drawings in which Fig. 1 is a sectional elevation on line 1—1 of Fig. 2, the swinging window being shown in closed adjustment; Fig. 2 is a front view from the interior of a room containing the window, parts being broken away and other parts being shown in section; Fig. 3 is a view showing the window frame in section and parts within the frame in section and in elevation, some portions being broken away, the swinging window being shown in open adjustment; Fig. 4 is a detailed view of the device employed for holding the end of the link that directly cooperates with the sliding sash in proximity to this sash, this device being shown,

in full lines, in an adjustment in which the link has its greatest effective length, an alternative adjustment being shown by dot and dash lines that permits the effective length of the link to be shortened; Fig. 5 is 00 a sectional view on line 5—5 of Fig. 2; Fig. 6 is a sectional view on line 6—6 of Fig. 2; and Fig. 7 is a perspective view of the link and the parts in cooperating relation thereto.

The sliding window sash 1 and the swinging window sash 2 may be suitably mounted within the window opening 3 which is formed in the wall 4 or other part that is to be provided with the window. In the 70 embodiment of the invention illustrated, I have shown a window frame in which the sashes are mounted, this window frame being desirably formed of channel iron 5 at its top side and angle iron 6 upon its remaining sides. A rib 7, preferably formed of channel iron, is located upon the upright and bottom sides of the window frame. The sliding window sash 1 has its frame 8 desirably formed of channel iron, the upright and bottom sides of this frame receiving the rib 7, the vertical portions of this rib guiding the sash 1 with its vertical sliding movement. The swinging window sash 2 has its frame 9 preferably formed of 85 angle iron. The top side of this frame 9 carries trunnion shafts 10 which are journaled within the upper ends of the upright side portions of the rib 7 and also, desirably, in the upper ends of the upright sides of 90 the window frame itself.

A link 11 is connected at its outer end with the lower side of the frame 9 of the swinging sash 2 midway between the ends of this frame side. I have shown an ear 12 95 upon the frame 9 through which a pintle 13 is passed, this pintle also passing through the outer end of said link. The inner end of the link has a downwardly deflected continuation 14 which is receivable between the ears 15 that are provided upon the frame 8 of the sliding sash at the top of this sash and midway between the upright sides of this sash. A U-shaped assembling device 16 has a long side which is horizontally 100 movable through holes provided in the bottom ends of the ears 15 and a short side receivable in holes provided at the upper ends of these ears and also receivable in an opening 17 formed through the deflected 105 110

end portion 14 of the link. The assembling device 16 is thus adjustable to either assemble the inner end of the link 11 with the sliding sash or to free the inner end of said link from direct assembly with the sliding sash. When the inner end of the link is directly assembled with the sliding sash, the link is of greatest effective length and the swinging sash is swung to its outermost position for any given position of the sliding sash, the extent to which the swinging sash projects outwardly and the degree of its slope depending upon the vertical position of the sliding sash.

15 The link 11 desirably has holding formations, preferably in the form of notches 18, which are distributed along the link and each of which is capable of individually receiving one of the walls of the channel iron portion that forms the top side of the frame 8 of the sliding sash. These notches enable the effective length of the link to be reduced so that the angularity of the swinging sash and the extent to which it

20 projects outwardly is lessened for any given position of the sliding sash. An upright guard 19, preferably in the form of a U-shaped loop that is journaled upon the bottom side of the U-shaped assembling device

25 16 embraces the link 11 in a manner to hold the deflected link end portion 14 in lapping relation to the top side of the frame 8 so that the link can not be moved, at its inner end, clear of the sliding sash, said guard

30 19 also holding the inner end of the link in proximity to the upper end of the sliding sash so that the link can never be swung clear of the upper end of this sash to such an extent that it would do bodily harm if

35 it were to fall from its elevated position.

The means for holding the guard 19 in its upright position desirably resides in lugs 20 which project outwardly from the ears 15 and which are so positioned as to confine the guard closely against the top side of the frame 8. The sliding sash is desirably held in various positions to which it may be adjusted by means of the cooperating holding members. One of these holding members is desirably in the form of a weighted dog 21 pivoted upon the ear 22 which is carried by an upright side of the sliding sash frame 8. A second holding member which cooperates with the holding dog 21 desirably comprises an upright side portion of the rib 7 which is formed with notches or other holding formations 23 spaced apart along the same. The sliding window sash should be raised to a position

40 in which the dog 21 will be receivable in some notch 23, the weight 24 upon the dog then causing the dog to extend into such notch.

Changes may be made without departing

Having thus described my invention, I claim:

1. The combination with a window having two sashes, one mounted to slide along the window frame and the other mounted to swing; of a link attached to the second sash and adjustably connected therealong with the first sash whereby the effective length of the link is adjustable to regulate the angularity of the sashes. 75

2. The combination with a window having two sashes, one mounted to slide along the window frame and the other mounted to swing; of a link attached to the second sash and adjustably connected therealong with the first sash whereby the effective length of the link is adjustable to regulate the angularity of the sashes; and means for holding the first sash in various adjustments and operating through the first sash to hold the second sash in adjustment. 80

3. The combination with a window having two sashes, one mounted to slide along the window frame and the other mounted to swing; of a link attached to the second sash and adjustably connected therealong with the first sash whereby the effective length of the link is adjustable to regulate the angularity of the sashes; and means for holding the first sash in various adjustments and operating through the first sash to hold the second sash in adjustment, said means comprising an elongated member having holding formations spaced apart along the same and a second member in the form of a holding dog engageable with said holding formations, one of said members being arranged upon the window frame and the other upon the first sash. 95

4. The combination with a window having two sashes, one mounted to slide along the window frame and the other mounted to swing; of a link connecting the sashes; and means for adjusting the effective length of the link to regulate the angularity of the sashes. 105

5. The combination with a window having two sashes, one mounted to slide along the window frame and the other mounted to swing; of a link connecting the sashes; means for adjusting the effective length of the link to regulate the angularity of the sashes; and means for holding the first sash in various adjustments and operating through the first sash to hold the second sash in adjustment. 115

6. The combination with a window having two sashes, one mounted to slide along the window frame and the other mounted to swing; of a link connecting the sashes; means for adjusting the effective length of the link to regulate the angularity of the sashes; and means for holding the first sash in various adjustments and operating through the first sash to hold the second sash in adjustment. 125

sash in adjustment, said means comprising an elongated member having holding formations spaced apart along the same and a second member in the form of a holding dog engageable with said holding formations, one of said members being arranged upon the window frame and the other upon the first sash.

7. The combination with a window having two sashes, one mounted to slide along the window frame and the other mounted to swing; of a link attached at one end to the second sash and deflected at its other end and notched between its ends and engageable, where notched, with the first sash whereby said link is adjustably connected therealong with the first sash; means for separably pivotally connecting the deflected end portion of the link with the first sash; and a guard upon the first sash and engaging the link and maintaining it in proximity to this sash.

8. The combination with a window having two sashes, one mounted to slide along the window frame and the other mounted to swing; of a link attached at one end to the second sash and deflected at its other end and adjustably connected therealong with the first sash; means for separably pivotally connecting the deflected end portion of the link with the first sash; and a guard upon the first sash and engaging the link and maintaining it in proximity to this sash.

9. The combination with a window having two sashes, one mounted to slide along the window frame and the other mounted to swing; of a link attached at one end to the second sash and notched between its ends and engageable, where notched, with the first sash whereby said link is adjustably connected therealong with the first sash; means for separably pivotally connecting the other end of the link with the first sash; and a guard upon the first sash and engaging the link and maintaining it in proximity to this sash.

10. The combination with a window having two sashes, one mounted to slide along the window frame and the other mounted to swing; of a link attached at one end to the second sash and adjustably connected therealong with the first sash; means for separably pivotally connecting the other end of the link with the first sash; and a guard

upon the first sash and engaging the link and maintaining it in proximity to this sash.

11. The combination with a window having a sash mounted to swing; of a link attached at one end to said sash and deflected at its other end and notched between its ends, the window having an element with which said link is engageable, where notched, with the aforesaid window element whereby said link is adjustably connected therealong with said window element; means for separably pivotally connecting the deflected end portion of the link with said window element; and a guard upon said window element and engaging the link and maintaining it in proximity to said window element.

12. The combination with a window having a sash mounted to swing; of a link attached at one end to said sash and deflected at its other end and adjustably connected therealong with said window element; means for separably pivotally connecting the deflected end portion of the link with said window element; and a guard upon said window element and engaging the link and maintaining it in proximity to said window element.

13. The combination with a window having a sash mounted to swing; of a link attached at one end to said sash and notched between its ends, the window having an element with which said link is engageable, where notched, with the aforesaid window element whereby said link is adjustably connected therealong with said window element; means for separably pivotally connecting the other end of the link with said window element; and a guard upon said window element and engaging the link and maintaining it in proximity to said window element.

14. The combination with a window having a sash mounted to swing; of a link attached at one end to said sash and adjustably connected therealong with said window element; means for separably pivotally connecting the other end of the link with said window element; and a guard upon said window element and engaging the link and maintaining it in proximity to said window element.

In witness whereof, I hereunto subscribe my name.

ARTHUR A. JAHR.
